Attorney

UNITED STATES PATENT OFFICE.

MARTIN SACHSE, OF RACINE, WISCONSIN.

VENTILATOR VALVE FOR WINDOWS.

Application filed July 30, 1925. Serial No. 47,117.

The invention relates to means for controlling ventilation of a room and has for its object the provision of a slide valve adapted to be attached to the lower rail of a window sash to control the passage of air through an opening in the sash.

A further object of the invention is the provision of a valve comprising a metal plate having its longitudinal edges bent to form guides and plates slidably mounted in said guides, the meeting edge of one of the plates being offset to overlap the meeting edge of the other plate and each of the plates provided with an offset tongue formed by parallel incisions, said tongues forming stops to limit the movement of the plates.

The construction and operation of the invention will be described in detail herein-after and the construction will be found 20 illustrated in the accompanying drawings in which

Figure 1 is a view in elevation of the rear of the plate,

Figure 2 a front view in elevation showing the plate applied to a window sash, illustrated fragmentally,

Figure 3 a longitudinal sectional view on a plane indicated by the line 3-3 of Figure 2, and

Figure 4 a transverse sectional view on the plane indicated by the line 4-4 of Figure 2.

In the drawings similar reference characters will be used to designate corresponding parts throughout the several views.

The improved ventilator valve comprises a plate 1 having its longitudinal edges bent back on the plate and spaced therefrom as shown at 2 to form guides to slidably receive the valve plates 3 and 4. The outer 35 ends of valve plates 3 and 4 are bent on themselves, and then at right angles to the planes of the plates as shown at 5 to form handles for the operation of the plates in opening and closing them.

The inner edge of plate 4 is offset as shown at 6 to overlap the corresponding inner edge of plate 3 to form a substantially air-tight joint when the plates are in closed position as shown in the drawings. Plate 4 is also 45 formed with an integral tongue 7 formed by

making parallel incisions in the ends of the plate and bending the tongue outwardly from the plate as shown, said tongue serving to engage the meeting edge of plate 3 when the plates are in a closed position, and also 55 serving as a stop to engage the end of opening 8 in plate 1. Plate 3 is also provided with an outwardly projecting tongue 9 constructed similarly to tongue 7 and serving as a stop to limit the outward movement of 60 plate 3 in opening the plate. As shown in Figure 2 the ends of the bent back portions 2 are inclined as shown at 10, and said inclined ends serve as stops to limit the inward movement of the plate by engaging the angular portions 5.

In use, the device is attached to a window sash, and preferably the lower rail of the sash as indicated at A, said sash being provided with an elongated opening B corresponding to the opening 8 in plate 1, and plate 1 is secured to the rail A by means of driven fastenings 11 engaging openings 12 adjacent to the ends of the plates. It will be apparent that when the device is in position as shown in the drawings, plates 3 and 4 may be manipulated to partly or entirely open the passage through openings B and 8, or ventilation may be entirely closed by closing the plates.

What is claimed is:-

A ventilator valve adapted to be secured to a window sash and to control the passage of air through an opening therein comprising a plate adapted to be secured on a sash and having an opening therein aligned with an opening in the sash, guides on the longitudinal edges of the plate formed by folding said edges, valve plates slidably mounted in said guides, one of said valve plates having its edge meeting the other plate offset to overlap the adjacent edge of the other plate, and each of said plates having a tongue cut therefrom by substantially parallel incisions and bent outwardly of the plates to provide stops to limit the movement of the plates.

In testimony whereof I affix my signature.

MARTIN SACHSE.
